ADJUSTABLE FASTENING DEVICE PARTICULARLY ADAPTED FOR ADJUSTABLY SECURING TOGETHER TWO ENDS OF A GARMENT

Paul Bauder, Heubach, Wurttemberg, Germany, assignor to Triumph Bekleidungs u. Textilwerke G. m. b. H., Heubach, Wurttemberg, Germany

Application September 14, 1953, Serial No. 380,036

2 Claims. (Cl. 2—42)

This invention relates generally to fastening devices of adjustable length, and particularly relates to a fastener for removably securing together the two back portions of a brassiere for the purpose of adjusting the width thereof. Among the numerous types of known adjustable fasteners there exists a preferred fastener where one of the ends of the fastening means, which usually consists of a ribbon or tape provided with pockets or loops, open at both ends while the other end of the fastening means includes a hook open on one side. In order to adjust the brassiere to a wider or narrower width the hook may be selectively engaged with one of the pockets or loops whereby the effective length of the fastening means is adjusted.

However, the known fastening means of this type still have great drawbacks.

In general, their manufacture is not yet sufficiently simple for such a mass-production article. Furthermore, in the old fastening means the elasticity of the fastening tape or ribbon is limited, for example by sewing of the loops to non-elastic fabrics, ribbons and the like. Finally, the known fastening means were not satisfactory because the wearer of the brassiere had difficulties to perform the necessary manipulation for engaging the hook with the desired pocket or loop which had to be done on the back of the wearer.

It is accordingly an object of the present invention to provide an improved fastening means, particularly adapted for adjustably securing together the back ends of a brassiere.

A further object of the invention is to provide an improved adjustable fastener that will avoid one or more of the drawbacks of prior art fasteners.

This is effected in accordance with the present invention by providing a fastener ribbon consisting of two elastic ribbon-like layers which are connected together by weaving in such a manner that weaving edges or lines are created which are suitably spaced apart, extend at right angles to the longitudinal axis of the ribbon and form pockets or loops open at least on one side thereof so that a hook or hooks may be inserted at will into any one of the pockets.

Such a ribbon may be manufactured very simply and cheaply. It has excellent elasticity along its entire length in spite of the pockets formed therein.

In accordance with a further feature of the invention the lower layer or portion of the ribbon which faces the skin of the wearer of the brassiere is made wider than the upper layer. The lower ribbon layer is disposed with respect to the upper layer in such a manner that both layers are flush along one longitudinal edge while the lower layer forms a projecting portion along the other longitudinal edge of the ribbon. This projecting portion serves as support and guiding surface facilitating the introduction of the fastening hook into one of the pockets.

By using such an arrangement the additional advantage is obtained that the fastening hook may be introduced more easily, securely and simply into that pocket

2

which guarantees the correct width and the best fit of the brassiere. The projecting portion then prevents in a simple and effective manner a sliding off of the fastening hook and facilitates the introduction of the hook into the selected pocket by spreading apart of the two walls of the selected pocket.

The invention is shown by way of example in the accompanying drawing, wherein:

Fig. 1 is a plan view of a portion of the fastener ribbon 10 of the invention on enlarged scale;

Fig. 2 is a sectional view of the ribbon taken on line II—II of Fig. 1;

Fig. 3 is a plan view of the fastening means of the invention used for fastening a brassiere, one end of the ribbon being secured to the one back portion of the brassiere; and

Fig. 4 is a plan view of another modification of the invention wherein the fastener ribbon is completely removable.

Referring now to the drawing and particularly to Figs. 1 and 2, there is illustrated an elastic ribbon or tape which forms part of the fastening means. The elastic fastener ribbon is either connected or secured with its one end to one of the two back portions of the brassiere or is arranged as a separate, removable member. This fastener ribbon is provided with a large number of adjacent pocket-like or loop-like compartments. Furthermore, there is provided a second fastening means which may, for example, be secured by means of a ribbon loop to the other back portion of the brassiere and which consists of a hook which is open on one side and which is engageable with one of the pockets.

The portion of the fastening means arranged in accordance with the invention consists of two layers 1 and 35 2 of an elastic fabric of tape-like or of ribbon-like shape, as is conventional for rubber ribbons used for many purposes.

A ribbon of this type is woven in a manner well known in the art of weaving ribbons in such a way that the 40 upper layer of the ribbon is securely united with the lower ribbon along straight lines spaced apart one or several centimeters. The individual weaving lines between the two ribbon layers 1 and 2 which effect such a union of the layers are shown in dotted lines at 3. They extend, as shown for example in Fig. 1, along straight lines which are at right angles to the longitudinal axis of the ribbon. It is feasible to weave the ribbon in such a manner that the weaving lines are hardly visible on the outer surfaces of the ribbon.

As clearly shown in Fig. 2 pockets or loops are formed by the two ribbon layers 1 and 2 which are woven in the manner above described. These pockets may be open on both sides. In some cases, however, it may be sufficient if only one side of each of the pockets is open, while the other side of each pocket may be closed, for example, by a weaving edge extending along the longitudinal direction of the ribbon.

As shown in Figs. 3 and 4, the hook 12 of the fastening means 8 or 8' may selectively be inserted into one of the pockets. When the hook 12 is inserted and a pull is exerted on it, such as occurs naturally when the wearer puts on the brassiere, the inner edge of the hook engages the weaving edge 3 which limits or defines the selected pocket.

As illustrated in Fig. 1, the lower ribbon layer 2 which is in contact with the skin when the brassiere is worn and which may be roughed, in a manner not shown, on its outer surface to achieve a padding effect has a larger width than the upper ribbon layer 1. The position of the lower ribbon layer 2 with respect to the upper layer is such that the two ribbon edges are flush along one longitudinal edge while on the opposite side the lower layer projects

beyond the upper layer. The projecting portion 4 of the lower ribbon layer 2 forms a guiding and supporting surface which facilitates insertion of the hook 12 into one of the pockets and thus facilitates considerably the correct insertion of the hook.

The hook 12 has a thickened head disposed at the end of its free leg which is bent along the direction of the pulling strain. The width of the upper ribbon layer 1 is chosen so that the free leg of the hook after insertion into one of the pockets extends beyond the opening of the pocket. This head hence acts as an automatic lock which prevents loosening of the fastener because the head is disposed against the weaving edge of the upper ribbon layer 1 in the manner of a locking pawl.

The fastener of the invention may not only be used for various purposes but may also be utilized in various ways.

Fig. 3 illustrates by way of example the utilization of the fastener of the invention as a back fastener for a brassiere. The ribbon of the invention is generally shown at 6. It is securely fastened to the back portion 7 of the brassiere. 8 generally indicates the fastening means including the hook 12. A simple elastic 11 is secured to the other back portion 10 of the brassiere by sewing and is formed into a loop and extends through the eye 9 of the fastening means 8. The hook 12 which is open on one side is engaged with or introduced into one of the pockets in the ribbon 6.

In accordance with the embodiment illustrated in Fig. 4, short elastics 13 are sewed to the two back portions 7 and 10 of a brassiere which is only partly shown. The elastics are formed into loops which extend through the eyes of the fastening means 8' which are thus secured to the two back portions of the brassiere.

The ribbon fastener 6' is a separate portion of the fastening device which has a length indicated in Fig. 4 and which may be simply removed when it is desired to wash the brassiere. Each of the two hooks 12 of the fastening means 8' may be inserted into one of the pockets depending upon the desired length of the fastening device. Otherwise, the arrangement of the ribbon fastener 6' is identical with that of Figs. 1 or 3.

Since certain changes may be made in the above article and different embodiments of the invention could be made

without departing from the scope thereof, it is intended that all matter contained in the above description or shown in the accompanying drawing shall be interpreted as illustrative and not in a limiting sense.

Having thus described the invention, what I claim as new and desired to be secured by Letter Patent, is as follows:

1. In a brassiere an adjustable elastic closure device to be applied to the two brassiere ends and comprising a closure hook composed of a pin having one rounded end and transiting with the other end into a closed eye portion, an elastic strip connecting said closure hook with an end portion of said brassiere, a superposed double layer strip of an elastic material fastened with its one end to the second rear end portion of said brassiere, the upper and the lower material layer of said double-layer strip being sewed together along parallel cross lines to form adjacent pockets and the lower material layer of said double-layer strip projecting beyond the upper material layer and forming a guide pocket to facilitate the entrance of said closure hook pin into the latter.

2. In a brassiere an adjustable elastic closure device to be applied to the two brassiere ends and comprising a closure hook composed of a pin having one rounded end and transiting with the other end into a closed eye portion, an elastic strip connecting said closure hook with an end portion of said brassiere, a superposed double layer strip of an elastic fabric material and the upper and the lower material layer of said double-layer strip being sewed together along parallel vertical cross lines to form adjacent pockets and the lower material layer of said double-layer strip projecting beyond the upper material layer and forming a guide pocket to facilitate the entrance of said closure hook into the latter.
